UNITED STATES PATENT OFFICE.

VIKTOR STEPHAN, OF PLAUE, GERMANY.

MACHINE FOR CASTING STEREOTYPE PLATES.

Application filed April 3, 1925. Serial No. 20,431.

To all whom it may concern:

Be it known that I, VIKTOR STEPHAN, a citizen of the German Republic, and a resident of Plauen, Saxony, Germany, have invented certain new and useful Improvements in a Machine for Casting Stereotype Plates, of which the following is a specification.

In the manufacture of machines for casting stereotype plates particular attention must be given to constructing the machines in such manner that the shell can be removed easily and quickly from the core on opening the mold, in order to facilitate the taking out of the stereotype plate and the renewal of the matrix. For this reason, as is well known, with an upright mold the shell rests on a curved guide in such manner as to fall automatically from a perpendicular into a horizontal position, when the core is lifted, whereby the center of gravity of the shell is neither lifted nor lowered. With a horizontal mold on the other hand the shell is moved downward in an oblique direction away from the core. Its weight has for this reason in certain instances been neutralized by appropriately disposed counter-weights. Where this means is not resorted to, however, the mold can only be opened and closed by motor power and a corresponding expenditure of energy. In all machines now in use the opening gear of the mold is accordingly very complicated. In many instances a number of operations are even necessary to open and close the mold, which in a printing shop require an expenditure of time which is not to be underestimated and which may even lead to blunders and errors.

Compared with devices now in use an essential simplification of the machinery necessary for opening and closing the mold as well as the tending is attained by means of the present invention. This is effected by allowing the shell to swing like a door on a perpendicular pivot at either side, whereby it can readily and quickly be opened and closed as well as locked in closed position by means of a joint-lever gearing.

One form of construction of the invention is shown in the accompanying drawings, in which Fig. 1 shows a vertical section of the casting mechanism. Fig. 2 is a front view, Fig. 3 a plan view of same. Fig. 4 elucidates the locking mechanism of

the opening and closing means of the gear channels of the mold.

The core 2 is fastened to the frame 1 of the casting machine. A supporting shaft 5 is also supported vertically in the frame 1 through bearings 3 and 4, said shaft serving as pivot for the shell 6. The latter can thus swing on the shaft 5 by means of the two arms 7 and 8 and their bearing eyes 9 and 10. The weight of the shell is supported by means of a roller not shown in the drawing, on the plate 25.

A perpendicular shaft 15 is revolubly mounted in the core 2. This shaft is fastened at its upper end to a hand lever 16 provided with a curved piece 17 operating on an adjustable roller 22 on the shell, for the purpose of locking the shell 6 in closed position. The lower end of shaft 15 is fastened to a lever 18, on which the guide 20 can turn by means of pin 19. The other end of the guide 20 engages the lower side of the shell 6 by means of a pin 21.

By turning the lever 16 the shell 6 is accordingly not only unlocked on the roller 22, but the lever 18 is also swung into the opening position 18 shown by dashes and dots in Fig. 3, whereby the guide 20 reaches the position 20' in the same figure, the shell coming into position 6'. When this has taken place, the previously cast stereotype plate can readily be taken out and the matrix renewed. In order to safely secure the cast stereotype plate to the core on opening the mold, supporting rods have been provided on the core in a manner yet to be described.

In closing the mold the lever 16 only has to be turned in the described direction either by hand or by motor power, whereby the mold is closed at once by means of the lever and guide 18, 20 and locked by means of the joint lever effect of the parts 18 and 20. At the same time the upper part of the shell 6 is pressed in its closed position against the core 2 by the curved piece 17 of lever 16 through roller 22. In this manner the mold is quickly and securely opened and closed by turning a single lever.

In order to prevent the opening of the gear channels of the mold at the wrong time, it is advisable to provide the bearing-eye 9 of the shell 6 with a lock-disk 26 which is carried along, when the mold is opened, and catches a steel plate 28 on lever

27 in such manner that said lever 27, by means of which an opening valve 29 for the gear channel 30 is governed, cannot be turned. Since lever 27 is furthermore connected by means of a rod 31 with lever 32 controlling the opening of valve 33 for gear channel 34, the latter cannot be opened as long as the lock disk 26 is in front of lever 27 or the steel block 28 attached to same. The lock-disk 26 and the steel plate 28 may further be regulated with respect to each other, so that the opening valves 29 and 33 can only be set by means of levers 27, 32 which are governed by hand lever 35, when the mold is completely closed.

In order to secure the cast stereotype plate firmly to the core 2 on opening the mold, but at the same time to facilitate its removal, horizontal adjustable supporting rods 41, 42, 43, 44 are provided on core 2. These supporting rods extend along the narrow longitudinal edges of the mold into the same. The projecting ends of the upper supporting rods 43, 44 are in this case constructed according to Fig. 1 in such a manner as to hold the cast plate like hocks. On the other hand the free ends of the lower supporting rods 41 and 42 have only conical ledges which, however, also serve to securely hold the cast plate.

The above mentioned four supporting rods are allowed to slide in the direction of their axles in core 2 of the mold and are constructed as tooth-racks in the middle, so that they can be shifted by means of cog-wheels 45, 46, 47 and 48. These cog-wheels are arranged in pairs on two horizontal shafts 49 and 50 turning in frame 1 of the casting machine, said shafts being connected with each other by means of levers 51, 53 and rods 52 in such a manner that both shafts 49 and 50 with their cog-wheels and by means of the latter all four supporting rods 41, 42, 43, 44 are uniformly moved.

In order to drive this mechanism one end of shaft 49 is fitted with a bevel-wheel 54 which engages a bevel-wheel sector 55 on a vertical shaft 56, said shaft being further fitted with a roller carrying lever 57. The latter on opening the mold is moved by the lateral curved surface 58 provided on lever 18, whereby, as will readily be seen, the supporting rods 41, 42, 43 and 44 are moved slightly out of the core of the mold. In doing so they carry the stereotype plate with them, suspending the same freely, but at the same time securing it tightly, until it is taken off by the workman tending the machine.

60 I claim:

1. In a machine for casting stereotype plates, in combination: a shell-mantle; a vertical spindle located laterally from said mantle and being hinged to it; another vertical spindle; a joint-lever mechanism

jointed at one end to the shell-mantle and at the other end to said latter spindle; and means to turn this spindle, the arrangement of the parts being such that the said shell-mantle can be opened and closed, as well as locked in its closed position, by said joint-lever mechanism substantially as set forth.

2. In a machine for casting stereotype plates, in combination: a shell-mantle; a vertical spindle located laterally from said mantle and being hinged to it; a locking disk connected with said shell-mantle; a system of levers controlling the gear channels of the shell-mantle and being adapted to keep them closed if the said shell-mantle is not completely closed, substantially as set forth.

3. In a machine for casting stereotype plates, in combination: a shell-mantle; a vertical spindle located laterally from said mantle and being hinged to it; another vertical spindle; a joint-lever mechanism jointed at one end to the shell-mantle and at the other end to said latter spindle; and means to turn this spindle, the arrangement of the parts being such that the said shell-mantle can be opened and closed, as well as locked in its closed position, by said joint-lever mechanism; a locking disk connected with said shell-mantle; a system of levers controlling the gear channels of the shell-mantle and being adapted to keep them closed if the said shell-mantle is not completely closed, substantially as set forth.

4. In a machine for casting stereotype plates, in combination: a shell-mantle; a vertical spindle located laterally from said mantle and being hinged to it; another vertical spindle; a joint-lever mechanism jointed at one end to the shell-mantle and at the other end to said latter spindle; means to turn this spindle; a shell-core arranged on the spindle mentioned in the second case; a plurality of bearing rods supported in said shell-core and being shiftable longitudinally and some thereof being hook-shaped at their front-ends; a gearing actuated automatically when the shell-mantle is being opened and transmitting motion to said bearing rods, substantially and for the purpose as described.

5. In a machine for casting stereotype plates, in combination: a shell-mantle; a vertical spindle located laterally from said mantle and being hinged to it; another vertical spindle; a joint-lever mechanism jointed at one end to the shell-mantle and at the other end to said latter spindle; and means to turn this spindle, the arrangement of the parts being such that the said shell-mantle can be opened and closed, as well as locked in its closed position, by said joint-lever mechanism; a shell-core arranged on the

- spindle mentioned in the second case; a plurality of bearing rods supported in said shell-core and being shiftable longitudinally and some thereof being hook-shaped at their 5 front-ends; a gearing actuated automatically when the shell-mantle is being opened and transmitting motion to said bearing rods, substantially and for the purpose as described.
- 10 6. In a machine for casting stereotype plates, in combination: a shell-mantle; a vertical spindle located laterally from said mantle and being hinged to it; a locking disk connected with said shell-mantle; a 15 system of levers controlling the gear channels of the shell-mantle and being adapted to keep them closed if the said shell-mantle is not completely closed; a shell-core arranged on the spindle mentioned in the 20 second case; a plurality of bearing rods sup-
- ported in said shell-core and being shiftable longitudinally and some thereof being hook-shaped at their front-ends, a gearing actuated automatically when the shell-mantle is being opened and transmitting motion to 25 said bearing rods, substantially and for the purpose as described.
7. In a machine for casting stereotype plates, the combination of a swinging shell, means for closing and opening said shell and locking the same in closed position, a shell-core, a plurality of longitudinally movable members supported in said shell-core and capable of locking the cast stereotype plate in position and automatically controlled 30 means for moving said members, when said shell is opened for removing said cast plate from said shell-core.

In testimony whereof I affix my signature.
VIKTOR STEPHAN.
